COMBINED SCISSORS AND HAIR SHAPER

Donald G. Tayler, 5842 Newman St.,
Cypress, Calif. 93214

Filed Jan. 24, 1966, Ser. No. 744

Term of patent 14 years

(Cl. D95—5)

FIG. 1

FIG. 2

FIG. 3

FIG. 4

FIG. 7

FIG. 5

FIG. 6

FIG. 1 is a front side elevational view of a combined scissors and hair shaper showing my new design; FIG. 2 is a rear side elevational view thereof;

FIG. 3 is a top plan view thereof;

FIG. 4 is a bottom plan view thereof;

FIG. 5 is a rear end elevational view thereof; and

FIG. 6 is a front end elevational view thereof.

I claim:

The ornamental design for a combined scissors and hair shaper, substantially as shown.
